UNITED STATES PATENT OFFICE.

WILLIAM HERBERT SEDDON, OF PAINSWICK, ENGLAND.

ROTARY ELASTIC-FLUID ENGINE.

1,231,437.

Specification of Letters Patent. Patented June 26, 1917.

Application filed March 31, 1917. Serial No. 159,038.

To all whom it may concern:

Be it known that I, WILLIAM HERBERT SEDDON, a subject of the Kingdom of Great Britain, residing at Painswick, Gloucestershire, England, clerk in Holy Orders, have invented certain Improvements in or Relating to Rotary Elastic-Fluid Engines, of which the following is a specification.

This invention relates to rotary elastic fluid engines, of the type comprising or involving a rotary cylinder base having a series of cylinders in which pistons are adapted to work, the said pistons coöperating with an element or elements adapted to rotate about an axis disposed eccentrically in relation to that of the rotary cylinder base. In one previously proposed arrangement, the pistons have been coupled to the outer ends of connecting rods, the inner ends of which 10 are articulated to eccentric straps disposed one on each side of the rotating cylinder base, these eccentric straps having been coupled to the base by links in order that they may rotate therewith. In another previously proposed arrangement the pistons have been coupled to the inner ends of connecting rods which extend outwardly to an eccentric ring encircling the cylinders, and which ring has been coupled to rotate with the said cylinders by links or by an Oldham coupling.

A feature of my invention has reference to the method of coupling or connecting the eccentrically mounted element or elements with the cylinder base or cylinders. The methods heretofore proposed, such as by the use of connecting links or an Oldham coupling, have the disadvantage that the eccentrically related elements have a differential speed of rotation. That is to say, while they rotate at the same number of revolutions per minute, during each cycle of rotation there is a part or parts of that cycle during which one of the elements temporarily advances in relation to the other. According to the present invention I incorporate between the eccentrically related elements, gearing which is of such a character that the eccentrically related parts rotate not only at the same number of revolutions per minute, but also at the same peripheral speed throughout each cycle of rotation so that with one of the said elements rotating at an even and uniform speed, the other element is likewise constrained to rotate at

this same even and uniform speed. In cases in which the construction involves eccentric straps disposed one on each side of the rotating cylinder base, the present invention furthermore insures, in a particularly efficient manner, that the said eccentric straps rotate in unison. 60

In order that this invention may be clearly understood and readily carried into practice, reference may be had to the appended 65 explanatory four sheets of drawings, upon which:

Figure 1 illustrates in sectional elevation an engine according to the present invention. 70

Fig. 2 illustrates in side elevation the engine shown in Fig. 1.

Fig. 3 illustrates in side sectional elevation, the engine shown in Figs. 1 and 2.

Fig. 4 illustrates in sectional elevation a 75 modified engine according to the present invention.

Fig. 5 illustrates in side sectional elevation the engine shown in Fig. 4.

In the drawings, *a* represents the hollow 80 bearing for the main rotor *b*. The latter rigidly carries a number of cylinders *c* which may be disposed radially. Each cylinder *c* contains a piston *d* which may be furnished with a rigid piston rod *e*; this 85 piston rod *e* passes out of the cylinder and is suitably coupled to a transverse cross-head *f*. The cross-head *f* is adapted to move in a radial path within guides *g* rigidly mounted in relation to the cylinders *c*. The 90 guides *g* of the several cylinders may be coupled together by connecting members *h* so that the rotor *b*, cylinders *c*, guides *g*, and connecting members *h* together form a rigid rotary structure. When a lateral stress is 95 being experienced by one or any of the guides *g*, such guides are, by virtue of the connecting members *h*, supported and reinforced by the other guides which are not at the time experiencing the stress. 100

Coupled to, or rigidly mounted in relation to, the central or main bearing member *a*, are supplementary bearing members *i* disposed one on each side of the main bearing member. These bearing members *i* are eccentrically disposed in relation to the central bearing member, and each member *i* carries an annular revoluble member *j*. To each annular revoluble member *j*, all of the connecting rods *k* occurring on one side of the 110

engine are coupled pivotally at their one extremities, the other extremities of such connecting rods *k* being pivotally connected to the respective cross-heads *f* appertaining to the pistons *d* to which the said connecting rods *k* are related. The revoluble members *j* are adapted to rotate at the same number of revolutions per minute as the main rotor *b*. For this purpose they are positively 5 geared together. In the arrangement shown in the drawings, the main rotor *b* has rigidly secured to it at each side, an internally toothed ring *l*. These toothed rings *l* gear with spur wheels *m* provided upon a shaft 10 *n* which is rotatably mounted in the stationary bearing member *a*. The spur wheels *m* mesh with spur wheels *o* provided upon a second shaft *p* also revolubly mounted in the stationary bearing member *a*. The shaft 15 *p* carries other spur wheels *q* which are in mesh with spur wheels *r* rigidly provided upon the revoluble members *j*. By this gear mechanism the revoluble members *j* are compelled to rotate in predetermined relationship with the main rotor *b*, and the correctly 20 timed operation of the pistons *d* within the cylinders *c* is thereby insured.

s is an axial conduit passing through one of the bearings *i* and adapted to provide for 25 communication with the interior of the hollow bearing member *a*. This hollow bearing member *a* contains two compartments *y, z*. The axial conduit *s* is sub-divided into two conduits, one of which communicates 30 with each of the chambers *y, z*. Into the space *y* explosive mixture is adapted to be introduced from any suitable source, and by any appropriate method, as for instance by use of a pump or blower. *t* is a port provided 35 in the peripheral wall of the stationary bearing member *a*. Other ports *u* are provided in the main rotor *b* and adapted to successively register with the port *t* in the stationary bearing member. As each cylinder 40 passes the port *t* in the stationary member, it is enabled to receive the explosive charge through its port *u*, the port *t* being appropriately positioned to provide for the ingress of this charge when the piston is in its outward position.

Any approved provision for firing the charge may be utilized. In the method shown in the drawing, a single sparking-plug *v* is utilized to successively fire the 45 charges in the several cylinders. This sparking-plug is mounted in the stationary bearing member *a*; its electrodes are disposed within a recess or depression *w* with which the ports *u* register. The depression *w* is disposed in such a position that each 50 port *u* registers with it as the piston of such port *u* is in its inward position. When the parts are in these positions the plug *v* is adapted by any suitable commutator to 55 spark, and thereby fire the charge. 2 is a

space within the hollow bearing member *a*, which space is isolated from the spaces *y, z*. This space 2 is open at one or both axial extremities thereby permitting of ready access being obtained to the sparking plug *v*. 70

By way of the appropriate sub-division in the conduit *s*, compressed air is admitted by any appropriate method to the space *z*. From this space *z* the said air is adapted to issue by way of a port *3* and as each port *u* 75 in the rotor occupies a position contiguous to the port *3* prior to its occupation of a position contiguous to the port *t*, air from the chamber *z* is thereby admitted to the cylinder for scavenging purposes. 80

The exhaust may be adapted to occur by way of openings such as *x* provided at or near the outer extremities of the cylinders, such openings being adapted to be uncovered by the pistons in the final parts of their 85 strokes. It will be noted that both the scavenging air and the mixture enter the radially inward extremities of the cylinders and flow radially outwardly in scavenging and charging said cylinders. 90

After the cylinder has been filled, and the contained charge is trapped by reason of the passage of the cylinder beyond the port *t*, compression takes place during the inward movement of the piston, this compression occurring around one-half of the cycle 95 of revolution until the charge in its compressed condition is fired. The engine thus acts upon the two-stroke cycle principle.

The exhaust outlets *x* may communicate 100 directly with the atmosphere, or they may communicate with an annular conduit having a common exhaust outlet.

The engine may be installed in any suitable manner, and the power transmitted 105 therefrom by any approved means. In the drawings the hollow ingress conduit *s* is shown extended beyond the rotary member *j* by which it is encircled, and this extended part of the conduit *s* may constitute the part 110 by which the engine is supported or installed, as for instance upon an aeroplane, the body of the engine projecting in cantilever formation. Provision (not shown) may, however, be incorporated if desired 115 for supporting the main stationary member of the engine on the side of the main central bearing *a* remote from that on which the conduit *s* occurs.

In the drawings, the supplementary rotary member *j* provided on the side of the main bearing portion *a* remote from that on which the conduit *s* occurs is shown furnished with an extension *j'*. From this extension *j'* the power may be taken in any 125 suitable manner; the extension may for instance carry the propeller of an aeroplane. 120

The cylinders, instead of being disposed radially in relation to their axis of rotation may be disposed tangentially to a circle of 130

any suitable radius struck from their axis of rotation.

Figs. 4 and 5 illustrate a modified construction of engine according to the present invention, in which the piston rods are dispensed with and the connecting rods 4 extend radially outwardly from the pistons 5 to an eccentrically disposed ring or member 6 encircling the cylinder. The connecting rods 4 are capable of a pivotal movement in relation to the pistons 5, and also in relation to the said ring or member 6, and said ring or member may, for instance, have spokes 7 extending inwardly to members 8 adapted to 10 rotate about an axis eccentric with that of the cylinders. These members 8 are equivalent to the members *j* in the embodiment shown in Figs. 1, 2 and 3, being in gear with the main rotor *b* by which the cylinders are 15 carried by the incorporation of gearing similar to that already described. In other respects, the engine illustrated in Figs. 4 and 5 is similar to that illustrated in Figs. 1, 2 and 3.

What I claim as my invention and desire to secure by Letters Patent is:—

1. The combination of a fixed structure having an outer bearing surface, an inner ring mounted to revolve on said bearing surface, an outer ring, cylinders fixed to said inner ring, pistons in said cylinders, links intermediate said pistons and said outer ring, a lateral projection extending from said fixed structure eccentrically thereof, a ring 30 mounted to rotate on said projection, rigid connections between said last mentioned ring and said outer ring, an internal gear fixed to said internal ring, an external gear fixed to said ring on said projection, and gearing 35 carried by said fixed structure coöperating with said internal and external gears for driving said last mentioned rings and said outer rings with said inner rings.

2. The combination of a fixed structure 45 having an outer bearing surface, an inner ring mounted to revolve on said bearing surface, an outer ring, cylinders fixed to said inner ring, pistons in said cylinders, links intermediate said pistons and said outer ring, a pair of lateral projections extending from 50 said fixed structure eccentrically thereof, a

ring mounted to rotate on each of said projections, rigid connections between said last-mentioned rings and said outer rings, an internal gear fixed to said inner ring, an external gear fixed to each of the rings on said projections, spindles carried by said fixed structure extending from side to side thereof, and gearing on said spindles coöperating with said internal and said external gears 60 for driving said last mentioned rings and said outer rings with said inner rings.

3. A rotary elastic fluid engine comprising in combination, a rotary cylinder base, cylinders on said base, pistons in said cylinders, 65 an outer member encircling said cylinders, rods pivotally connected to said outer member and to said pistons, eccentrically disposed rotatable members one on each side or axial face of said cylinder base and to which 70 said outer member is connected, a continuous gear on each axial face of said cylinder base, a continuous gear on each of said eccentrically disposed members, and gearing intermediate said gears on said base and said 75 gears on said eccentrically disposed members whereby said eccentrically disposed members operate in unison with each other and in synchronism with said base.

4. A rotary elastic fluid engine comprising 80 a rotary cylinder base having a series of cylinders thereon, pistons in said cylinders, members disposed one on each side or axial face of said base and mounted to revolve on an axis eccentric with respect to said base, 85 connections between said pistons and said eccentrically mounted members, a continuous gear on each side or axial face of said cylinder base, a continuous gear on each of said eccentrically mounted members, and gearing 90 intermediate said gears on said base and said gears on said eccentrically mounted members whereby said eccentrically mounted members operate in unison with each other and in synchronism with said base.

In testimony whereof I affix my signature in presence of two witnesses.

WILLIAM HERBERT SEDDON.
